US00D808921S

(12) **United States Design Patent** (10) **Patent No.:** **US D808,921 S**
(45) **Date of Patent:** **** Jan. 30, 2018**

(54) **RADIO COMMUNICATION DEVICE**

(71) Applicant: **ICOM INCORPORATED**, Osaka-shi, Osaka (JP)

(72) Inventor: **Haruki Nishizawa**, Osaka (JP)

(73) Assignee: **ICOM INCORPORATED**, Osaka (JP)

(**) Term: **15 Years**

(21) Appl. No.: **29/564,030**

(22) Filed: **May 10, 2016**

(30) **Foreign Application Priority Data**

Nov. 11, 2015 (JP) D2015-025199

(51) **LOC (11) Cl.** **14-03**

(52) **U.S. Cl.**

(57) **CLAIM**

The ornamental design for a radio communication device, as shown and described.

DESCRIPTION

FIG. 1 is a perspective view of the radio communication device;

FIG. 2 is a front view of the radio communication device;

FIG. 3 is a rear view of the radio communication device;

FIG. 4 is a left side view of the radio communication device;

FIG. 5 is a right side view of the radio communication device;

FIG. 6 is a top view of the radio communication device; and,

FIG. 7 is a bottom view of the radio communication device.

The broken lines depict portions of the radio communication device in which the design is embodied that are not considered part of the claimed design.

1 Claim, 7 Drawing Sheets
